US0D1027859S

(12) **United States Design Patent** (10) Patent No.: **US D1,027,859 S**
(45) Date of Patent: ** May 21, 2024

(54) **OUTDOOR ENERGY STORAGE EQUIPMENT**

(71) Applicant: **Eve Energy Storage Co., Ltd**, Wuhan (CN)

(72) Inventors: **Xuepei Xu**, Hubei (CN); **Yuncong Pang**, Hubei (CN); **Yulang Zou**, Wuhan (CN); **Changjun Shuai**, Hubei (CN); **Zhao Tian**, Hubei (CN); **Shilei Liu**, Hubei (CN); **Xiaomei Tang**, Hubei (CN); **Peiying Long**, Hubei (CN); **Zihui Zhao**, Hubei (CN); **Haohao Yi**, Hubei (CN); **Yubao Meng**, Hubei (CN); **Xiang Chen**, Hubei (CN)

(73) Assignee: **Eve Energy Storage Co., Ltd**, Wuhan (CN)

(**) Term: **15 Years**

(21) Appl. No.: **35/517,605**

(22) Filed: **Jun. 8, 2023**

(80) **Hague Agreement Data**

Int. Filing Date: **Jun. 8, 2023**

Int. Reg. No.: **DM/229679**

Int. Reg. Date: **Jun. 8, 2023**

Int. Reg. Pub. Date: **Jun. 23, 2023**

CLAIM

The ornamental design for outdoor energy storage equipment, as shown and described.

DESCRIPTION

1. Outdoor energy storage equipment

1.1 : Front

1.2 : Back

1.3 : Left

1.4 : Right

1.5 : Top

1.6 : Bottom

1.7 : Perspective

1.8 : Partial enlarged view of part A

1.9 : Partial enlarged view of part B

1.1-1.9 are drawings showing an embodiment of the outdoor energy storage equipment; 1.8 is a partial enlarged view of part A in 1.1; 1.9 is a partial enlarged view of part B in 1.7;

(Continued)

the present product is used for outdoor energy storage and for charging an equipment; the broken lines form no part of the claimed design.

1 Claim, 9 Drawing Sheets
